UNITED STATES PATENT OFFICE.

WILLIAM H. MCFARLEN, OF GARRISON, IOWA.

WASHING-MACHINE.

SPECIFICATION forming part of Letters Patent No. 272,292, dated February 13, 1883.

Application filed November 7, 1882. (No model.)

To all whom it may concern:

Be it known that I, WILLIAM H. MCFARLEN, of Garrison, in the county of Benton and State of Iowa, have invented certain new and useful 5 Improvements in Washing-Machines; and I do hereby declare the following to be a full, clear, and exact description of the invention, such as will enable others skilled in the art to which it pertains to make and use it, reference 10 being had to the accompanying drawings, which form part of this specification.

My invention relates to an improvement in washing-machines; and it consists in the combination of a socket, which is secured to the 15 side of the tub, with an arm or lever having one end bent so as to pass into the socket, and a connecting-rod for uniting this arm and the rubber together, as will be more fully described hereinafter.

20 The object of my invention is to adapt the rubber to be raised out of the tub, and be supported upon one end thereof while the clothes are being adjusted in position or the tub is being cleaned out.

25 Figure 1 is a side elevation of my invention complete. Fig. 2 is a vertical cross-section of the same.

A represents the tub, which is preferably made of a semicircular shape, and B the rubber, which is provided with a handle or lever, C, for moving it back and forth in the usual manner.

Secured to each side of the tub is a socket, D, and the arm F, which has one end bent vertically downward, is held in this socket, and has a vertical play therein.

Pivoted to the outer end of the arm F is the connecting-rod G, which has its inner end pivoted to a suitable casting, H, which is secured 40 directly to the side of the washer. The washer being pivoted upon this connecting-rod can be turned and moved freely in the usual manner

for washing the clothes, and when it is desired to place the clothes in the tub the washer can be raised upward out of the way and moved 45 backward so as to be supported upon one end of the tub. While the washer is thus held upon one end of the tub the tub can be cleaned out, left to dry, or the clothes packed in it.

The bottom of the tub will preferably be 50 made of zinc and covered with slats, and in order to allow the water and the dirt to always sink readily to the bottom without being caught by the slats two or more grooves, I, are made in the zinc bottom under the slats, so as to 55 allow the water and dirt to always run freely to the center. There will also be a groove made in each edge of the zinc bottom to receive the semicircular bottom edges of the sides of the tub. These grooves will be partly filled with 60 paint or white lead before the edges are inserted in them, and then when the parts are secured together a permanently water-tight joint is formed.

Having thus described my invention, I 65 claim—

1. The combination of the tub provided with sockets upon opposite sides, the arms which fit in the sockets, the connecting-rods which are fastened to the upper ends of the arms and to 70 the sides of the rubber, and the rubber, substantially as shown.

2. A washing-machine having a ribbed bottom, and having grooves made in the bottom under the slats, so as to allow the water and 75 dirt to run to the center of the tub, substantially as set forth.

In testimony whereof I affix my signature in presence of two witnesses.

WILLIAM H. MCFARLEN.
